FORM TIE

Henry H. Toogood, Los Angeles, Calif.

Application October 20, 1932. Serial No. 638,808

9 Claims. (Cl. 25—131)

This invention relates to concrete forms and more particularly to a wire form tie and form spreader or spacer.

An object of this invention is to provide a preformed tie and spreader or spacer for the form boards or walls so that during the mounting of the walls or sides of the form, certain portions of the sides will not be out of alinement with the other portions, thereby effecting the thickness of the concrete wall or floor construction.

Another object of this invention is to provide in a form tie means whereby after the concrete wall has been constructed and the form boards removed therefrom, moisture will not seep through the concrete construction along the surface of the tie or spreader under capillary attraction.

A further object of this invention is to provide a twisted wire tie and spreader which is so constructed that the strands of wire are subjected, under the twisting thereof, to substantially the maximum stretching capacity of the wire so that when the tie is in operative position, it will not stretch additionally under the strain of the concrete.

A still further object of this invention is to provide a twisted wire strand which is constructed initially out of a single strand of wire so looped or bent upon itself as to provide a plurality of wire strands having a configuration at a point intermediate the length of the tie to prevent the passage of moisture under capillary attraction through the concrete construction when the concrete has set.

The above and various other objects and advantages of this invention will in part be described and in part be understood from the following detailed description of the present preferred embodiment, the same being illustrated in the accompanying drawings wherein:—

Figure 1 is a detail top plan view partly broken away of a form tie before the wire strands are twisted upon each other.

Figure 2 is a top plan view of the completed form tie.

Figure 3 is a detail side elevation of the form tie shown in Figure 2.

Figure 4 is a fragmentary top plan view of another form of tie construction.

Figure 5 is a top plan view of a further form of tie construction.

Figure 6 is a top plan view of another form of tie construction.

Referring to the drawings wherein like numer-

als of reference designate corresponding parts throughout the several views, the numerals 10 and 11 designate the form boards or side walls of a form, which are adapted to receive a concrete construction such as a wall, floor or other concrete construction. In order to space the form boards or walls 10 and 11 apart the desired distance and to prevent spreading of these boards relative to each other, I have provided a form tie which is constructed out of a single piece of strand wire, which form tie is generally designated as 12.

The wire strand from which the tie 12 is constructed is first bent in the configuration shown in Figure 1 with the free ends thereof parallel with each other and terminating at a point adjacent one end of the looped strand. As shown in Figure 1, one portion 13 of the wire is provided with an angularly related stop member 14 which is adapted to abut against the inner surface of the form board 10, and the opposite end of this portion 13 is provided with an extension 15, which terminates in a U-shaped portion 16, and the connection between the U-shaped portion 16 and the extension 15 forms a loop 17, the purpose for which will be hereinafter described.

The opposite end portion 18 of the wire strand is also provided with a stop member 19 extending a direction oppositely from the stop 14 and engaging against the inner surface of the form board 10. This end portion 18 has a loop 20 at one end thereof which is initially adapted to substantially abut against the bight of the U-shaped member 16 and be disposed in substantially the same plane as the extension 16.

A loop 21 is connected to the loop 20 by means of a connecting bar 22, and this loop 21 is adapted to be disposed oppositely from the loop 20, and is adapted to receive a tie bar 23, which abuts against the outer surface of the form board 10. An extension 24 is formed with the loop 21 and extends across the space between the form boards 10 and 11 and is connected to the U-shaped tie rod engaging member 16 by means of an extension 25 which also terminates in a loop 26 normally spaced apart from the loop 17. A form tie bar 27 is adapted to be engaged in the bight of the U-shaped member 16 and to abut against the outer surface of the form board 11.

The construction shown in Figure 1 is diagrammatic and shows the initial formation of the tie rod hereinafter described before the strands 13, 18, 22 and 24 are twisted upon each other.

These strands 13, 18, 22 and 24 are twisted upon each other, as shown in Figure 2, and at a point intermediate the ends of this twisted portion, there is provided a loop, generally designated as 5 28, which constitutes a moisture block. This loop is constructed of pairs of the strands of wire 13, 18, 22 and 24, which are spaced apart from each other a desired distance so that a portion of the concrete when in moist or plastic form, 10 may be received between the pairs of strands, and the concrete may closely engage about the periphery of the wire strands so as to prevent the passage or movement of water or moisture along the periphery of the wire strands under 15 capillary attraction.

Where a form tie is provided which is constructed principally of wire strands twisted upon each other, the form tie acts as a guide member to permit the passage of water through the concrete under capillary attraction so that the inside surface of the concrete wall or concrete construction will be dampened when the outside surface of the concrete construction is also dampened. In this manner, where the inside surface 20 of the wall or the like forms a wall or interior of a building or the like, the material on the wall will be moistened and damaged by this moisture seeping along the twisted strands of wire. However, where a block or moisture stop is provided by means of the loop 28, the concrete within this loop and disposed about the parallel strands of wire will prevent the passage of water along the wire and thereby maintain the inner surface of the wall in a dry condition at all times. 25

30 The loop 20 is adapted to be bent at substantially a right angle to the longitudinal axis of the form tie, as shown in Figures 2 and 3, so that this loop 20 constitutes a spacing member cooperating with the spacing members or stops 40 14 and 19 in holding the form boards 10 and 11 the desired distance apart.

As shown in Figures 1, 2 and 3, the loop 21 is adapted to receive a form tie bar 23 and the loop 16 adapted to receive a second form tie bar 27. The two loops 17 and 26 may be turned so as to twist the extensions 15 and 25 and the parallel legs of the U-shaped member 16 so as to tighten the tie bar 27 within the bight of the loop member 16. In this manner, when the workman is mounting the tie member herein disclosed in the concrete form, the stop members 14, 19 and 20 will not only hold the form boards 10 and 11 apart the desired distance but also the U-shaped or loop member 16 will prevent movement of the bar 27 in the event the forks formed by the extensions 15 and 25 and the parallel legs of the member 16 are twisted unduly. 50

55 In Figure 5, there is disclosed another type of form tie which is constructed initially of a single strand of wire looped upon itself to provide three strands which are initially disposed in parallel relation one to another after the same manner as the strands shown in Figure 1, and the ends of the wire are twisted upon each other so as to provide a twisted strand or tie portion 29. At each end of this tie member 29, an angularly related spreader 30 is provided, each of which is adapted to engage against the inner surface of the form boards 10' and 11'.

70 One strand 31 of the triple strand tie construction shown in Figure 5 is disposed in spaced parallel relation to the twisted tie portion 29 and at each end of the strand member 31 and the member 29, there is provided a fork 32 which terminates in a U-shaped saddle or bar supporting

member 33. This saddle 33 is adapted to receive a tie bar 34, and this bar 34 is adapted to engage against the outer surface of the form members 10' and 11'.

Through the construction of a form tie, as shown in Figure 5, the concrete is adapted to closely engage about the twisted strands of wire, and due to the close twisting of the wire and to the fact that there are only two strands twisted one upon the other, the concrete will act as a moisture block, not only for the passage of moisture along the twisted tie portion 29, but also along the surface of the tie member 31 which is straight. 80

85 As shown in Figure 6, the form boards 10' and 11' are held in spaced relation to each other by means of a form tie constructed of three strands of wire which is initially a single wire strand looped upon itself in a manner to provide three parallel strands similar to the construction 90 shown in Figure 5. In Figure 6, however, the three strands are twisted upon each other in a manner to provide an intermediate moisture block in the form of a closed loop 35, which is of a construction similar to the moisture block 28. 95 In Figure 6, one of the wire strands terminates in a stop member 36 and another strand terminates in a stop member 37.

100 A loop 38 is provided at one end of the tie which engages about a bar 39 and at the other end of the tie, a forked member 40 is provided which has a substantially U-shaped saddle 41 formed therewithin the bight of which a bar 42 is adapted to seat and engage against the outer surface of the wall member 11'. 105

110 As shown in Figure 4, the form tie 12' is provided with an inner loop 20' which is left or disposed in alignment with the forked portion comprising the strand members 15', the saddle member 16' and the strand member or extension 115 25'.

120 In the use of the form tie constructions herein disclosed, where the form tie shown in Figures 2 and 3 is used, the loop 21 may be engaged with the rod 23 and the opposite end of the form tie passed between abutting form boards 11 and projecting outwardly beyond the outer surface thereof so that the forked portion of the tie together with the saddle 16 will be positioned beyond the outer surface of the form board 11. The stop 125 member 20 will limit the inward movement of the form board 11 so that each of these boards 10 and 11 will be spaced apart by means of the stop members 14, 19 and 20. The bar 27 is then positioned in the saddle 16 and the free ends of 130 the fork 17 and 26 then twisted so as to tighten the bar 27 within the saddle and against the outer surface of the form member 11. Due to the fact that during the twisting of the forked construction, there are four strands of wire 135 which are twisted upon each other, it is not easy to break the wire strands.

140 When the strands have been so twisted as to tightly engage the bar 27 in the saddle 16, the bar 27 will not only be held tightly within the saddle but also the form board 11 will be tightly pressed against the stop member 20 and in the same manner, the form board 10 will be pressed against the bar 16 and also against the stop members 14 and 19. When the concrete is poured 145 into the space between the form members 10 and 11, a portion of this concrete will be disposed within the loop 28 and this concrete will act as a block to prevent passage of moisture along the surface of the tie member 12. The tie members 150

shown in Figures 5 and 6 may also be engaged with the desired form boards and these members tightened by means of the forked end portions 32 and 40, respectively. The ties shown in Figures 5 and 6 can be used where a relatively light concrete construction is being formed, whereas the form tie shown in Figures 1 to 4 inclusive may be used where a relatively heavy tie construction is used.

10 While I have shown the tie members as being provided with one intermediate loop or moisture blocking member, I do not wish to be limited to this particular construction as, if desired, any number of these moisture blocks may be provided intermediate the ends of the tie and between the portions of the tie engaged by the form boards. Preferably, the moisture blocking loops are of a size such that the loop will not be contracted or reduced under the strain of the wet concrete or 20 the tension applied to the form tie by the forked loops at one or both ends of the tie.

It will be obvious, from the foregoing, that a preformed tie can be provided so that the form boards will be spaced apart the desired distance, thereby eliminating the necessity of measuring the distance apart of the form boards and also 25 eliminating undue pressure on the ends of the tie where the form boards bulge outwardly a slight distance.

30 This form tie embodies a construction such that where desired, the spacing members for spacing the form boards apart may be eliminated, in which case the forked bar holding member 16 will act to prevent movement of the form board 11 relative to the form board 10. In other words, the two loops 17 and 26 may be twisted so as to 35 tighten the bar 27 in the loop 16, and due to the construction of the loop 16, this loop cannot move relative to the opposite loop 21.

40 It will, therefore, be seen that where the spacing members 14, 19 and 20 are eliminated or flattened out, the tie can be used to hold the form boards in adjusted position and the forked loop 16 can be tightened without danger of the workman pinching in certain portions of the form boards as is the case where no spacing members are used in form ties of a construction not embodying the looped structure 16.

45 It is, of course, understood that various changes and modifications may be made in the details of construction and design of the above specifically described embodiment of this invention without departing from the spirit thereof, such changes and modifications being restricted only 55 by the scope of the following claims.

What is claimed is:—

50 1. A form tie comprising a single wire member looped upon itself to provide a plurality of strands, the strands being twisted about each other, a closed loop formed at one end of the twisted structure, an open loop formed at the other end of the twisted structure, means formed intermediate the ends of the twisted portion to prevent the passage of moisture therealong, and a saddle within the open loop.

55 2. A form tie comprising a single wire member

looped in a manner to provide a plurality of parallel wire strands twisted about each other to form a single tie member for embedding in concrete, a closed loop at one end of the tie member, an open loop at the other end of the tie member, the free ends of the open loop extending outwardly, and a saddle within the open loop.

80

3. A form tie comprising a single wire strand looped upon itself and twisted intermediate the ends of the looped portions to provide a single loop at one end, an intermediate twisted portion, an open loop at the other end with the opening of the loop directed outwardly, means intermediate the two loops to prevent movement of form boards positioned at each end of the twisted portion, and a saddle within the open loop.

85

4. A form tie comprising a member constructed of a single strand of wire looped upon itself and twisted to form a single intermediate tie portion, a closed loop at one end of the tie portion, an open loop at the other end of the tie portion, the opening of the latter loop extending outwardly, means formed intermediate the ends of the twisted portion to prevent passage of water or moisture therealong, and a saddle within the open loop.

95

5. A form tie comprising a member constructed of a single strand of wire looped upon itself, certain portions of the looped portions being twisted together to form a relatively rigid tie member, an open loop at each end of the tie member, and a saddle within each open loop.

105

6. A form tie comprising a member adapted to hold opposing walls of a form in spaced relation to each other, said member comprising a single wire strand looped upon itself in a manner to provide a twisted central portion, wall holding members at each end of the central portion, an open loop at one end of the central portion, the opening of said loop extending outwardly and the closed portion of said loop constituting a saddle to receive a wall engaging member therein, and loops formed with each side of the open loop to facilitate tightening of the wall engaging member within the closed portion of the loop.

115

7. A form tie, comprising a member constructed of a single strand of wire looped upon itself, certain portions of the wire being twisted together, and a substantially U-shaped saddle at an end of the tie member having the free ends thereof extending outwardly of the member.

125

8. A form tie, comprising a member constructed of a single strand of wire looped upon itself, certain portions of the wire being twisted together, a substantially U-shaped saddle at one end of the member having the free ends extending outwardly, and a pair of loops integral with the free ends of the member and disposed one on each side of the saddle.

130

9. A form tie, comprising a member constructed of a single strand of wire looped upon itself, a substantially U-shaped saddle at an end of the member, said saddle having the free ends thereof disposed outwardly, and a pair of loops integral with the free ends of the member and the tie.
